UNITED STATES PATENT OFFICE.

PERCY H. THOMAS, OF UPPER MONTCLAIR, NEW JERSEY, ASSIGNOR TO COOPER HEWITT ELECTRIC COMPANY, OF HOBOKEN, NEW JERSEY, A CORPORATION OF NEW JERSEY.

SYSTEM OF CAR OPERATION BY VAPOR-CONVERTERS.

1,157,824.

Specification of Letters Patent. Patented Oct. 26, 1915.

Original application filed August 2, 1905, Serial No. 272,352. Divided and this application filed January 22, 1913. Serial No. 743,480.

To all whom it may concern:

Be it known that I, PERCY H. THOMAS, a citizen of the United States, and resident of Upper Montclair, county of Essex, State of New Jersey, have invented certain new and useful Improvements in Systems of Car Operation by Vapor-Converters, of which the following is a specification.

The present invention relates to the application of vapor converters to systems involving the operation of moving cars from an alternating current supply main.

The invention contemplates employing a single converter or two or more converters in parallel with direct current motors in multiple or in series.

It is the object of the present invention to secure the advantages of alternating current distribution to approximately the points of utilization, such distribution being by means of polyphase or single phase transmission as desired and at the same time to secure the economy, the small size, and the generally favorable characteristics of the direct current series motor. This I accomplish by utilizing vapor rectifiers to secure the conversion of alternating to direct current and further locate these rectifiers in the immediate neighborhood of the motors. I propose obtaining these results by utilizing for the conversion of the alternating currents derived from the source vapor converters, and making use of the direct current thus produced for the propulsion of a car or cars.

A number of methods of starting are illustrated in the drawings and in some of them no method of starting the rectifier bulbs has been shown. It is not attempted to show all possible methods of starting, but any of those known in the art are applicable and may be applied.

My invention is illustrated in the accompanying drawings in which—

Figure 1 shows a method of simultaneously regulating a plurality of single phase rectifiers fed from a three phase source, Fig. 2 illustrates a system for feeding and controlling a railway load from a series of rectifiers fed from transmission mains having different supply sources, and Fig. 3 represents a system somewhat similar to that of Fig. 2 utilizing a three phase supply without a neutral conductor.

In Fig. 1 is illustrated a method of oper-

ating direct current motors shown at 17, 17, 55 from a three-phase source of supply connected with two trolley-wires, 1^a and 1^b, and with a return earth or metallic conductor, 2. The means of control are illustrated at 90, the same consisting essentially of choke-coils, 91, 92 and 93, surrounding a common core, 94. The voltage in the receiving circuit is adjusted by means of groups of transformers, 95, 95, interposed between the supply-circuit 1^a, 1^b and 2, and the receiving circuit. The vapor converters transmitting the supply to the several motors are shown at 96, 97, and 98. The controller, 90, is regulated by means of a pivoted arm, 99, which can be operated for lifting and lowering the core, 94, and thereby adjusting the current delivered.

Each converter is supplied with an inductance, 101, for keeping alive purposes and for starting purposes each converter is provided with a resistance, 102, and with a snap or quick-break switch, 103, already well-known in the art. Each converter is also supplied with a starting band, 104, near the negative electrode 15 which starting band is joined by a wire, 105, to one of the leads to a positive electrode within the converter. The leads to the positive electrodes are themselves supplied with inductances 106, as shown, partly for purposes of regulation and partly for preventing short-circuiting between the positive electrodes. In connection with the system I also supply inductances, 107, 107, 107, for obtaining the neutral point of the system.

The system illustrated in Fig. 2 includes means for applying quarter-phase and three-phase currents through poly-phase, three-phase or single-phase vapor converters to direct current bus-bars or feeder-wires connected with suitable motors. At the left in Fig. 2 I show at 108, 108, a source of quarter-phase currents the same being illustrated as transformers of different phase connected to four positive electrodes, 109, 109, 109, 109, in the converters 110, and 111. The negative electrodes 15 of the said converters are connected to one of the bus-wires, 112, while the supply bus bars are connected through intermediate points, of the transformer 108 windings 114 with the other bus-wire, 113. By the means indicated direct current is supplied to the bus-wires and may be trans-

ferred to suitable motors on a single car or a train of cars, as desired.

In the middle portion of Fig. 2 I show a source, 115, of three-phase current connected to three positive electrodes, 116, 116, 116, in the vapor converters 117 and 118. The negative electrodes 15 of the said converters are connected to the bus wire 112 either through inductances as shown at 118, or through resistances, as shown at 119.

The system here illustrated also supplies to the bus-wires direct current for any preferred utilization. The neutral point of the source, 115, is connected to the bus-wire, 113, by a conductor, 120 and suitable connecting means, 175. These means, 175, may operate in accordance with the principles of the apparatus shown at 114, 114, at the left of this figure or of the parts shown at 107 in present Fig. 1 or according to any other one of the various means for connecting the neutral of the supply source well known in the art. At the right hand side of Fig. 2 I show single-phase converters having positive electrodes, 121, 121, joined through inductances, 122, 122, 122, to the bus-wire, 112. This system of conversion is applicable to either the quarter phase or three-phase system of supply, as will be readily seen. Direct current motors are shown at 176 and 178, the first and last being series motors, and 177 being a shunt motor.

In Fig. 3 I illustrate a method of supplying direct current bus-bars from a polyphase or single-phase current source, the method consisting broadly in providing each converter or group of converters with a transformer of its own, as distinguished from an auto-transformer. In illustration, the source is assumed to be three-phase. From each phase a primary, 123, is taken, the several primaries being provided with secondaries, 124, 125 and 126. The terminals of the secondary 124 are connected to the positive electrodes, 127 127 in the vapor converter 128; the terminals of the secondary 125 are connected to the positive electrodes 129, 129, in the vapor converter 130 and the terminals of the secondary 126 are connected to the positive electrodes 131, 131, 131, 131, in the converters 132 and 133. The negative electrodes 15, 15 of the converters, 128 and 130, are connected through inductances 134, 134, to the bus-bar, 112, while the middle points of the secondaries, 124, and 125 are connected by conductors, 135 and 136, to the bus-bar, 113. At the same time, the middle point of the secondary 126 is connected by conductor, 137, to the bus-bar 113 while the negative electrodes 15 of the converters 132 and 133 are connected through inductances 139 and 140 to the bus-bar 112.

It is evident that each of the three-phases supplied by the sources of three-phase cur-

rent is provided with its own transformer, the current from which is applied to suitable secondary circuits to the converters illustrated in Fig. 3. It is also evident that the bus-bars 112, 113, receive direct current which may be applied in any suitable way to car motors or other translating devices.

The method of acceleration and control shown and described as applying to single-phase circuits are not intended to be limited to single-phase but may be utilized wherever suitable in connection with polyphase circuits and converters. It may sometimes be desirable to operate upon the same direct current system converters of different types or converters of the same type obtaining energy from different sources either of the same kind or of different kinds. This case is illustrated in Fig. 2. The sources referred to need not necessarily be located at the same station, but may be located at different points.

This case is a division of my application Serial Number, 272,352, filed August 2nd, 1905.

I claim as my invention:

1. In a system of electrical distribution, the combination with a three phase supply, three single phase rectifiers supplied by separate phases thereof, a common work circuit for said mercury vapor rectifiers and a separate inductance for each of said rectifiers whereby current is maintained continuous in each and the currents in the three phase supply are regulated.

2. In a system of electrical distribution, the combination of a three phase source of supply, a plurality of single phase mercury vapor rectifiers fed from separate phases thereof, a common work circuit for said rectifiers and separate inductances for said rectifiers whereby the operation of each is rendered independent of the others.

3. In a system of electrical distribution, the combination of a plurality of alternating sources of electricity, a direct current work circuit and a plurality of mercury vapor rectifiers connected between said sources and said work circuit, each rectifier having a plurality of main anodes, and means for causing the moments of maximum activity of similar anodes in the several rectifiers to occur at different instants of time whereby the uniformity of the rectified energy is increased.

4. In a system of electrical distribution, the combination with a plurality of sources of alternating current, a direct current work circuit and a plurality of mercury vapor rectifiers interposed between said sources and said work circuit, of means for causing the flow of energy in the several rectifiers occurring at different periods of time to overlap whereby a relatively steady rectified voltage is obtained.

5. In a system of electrical distribution, the combination with a plurality of non-synchronous sources of electric supply, separate rectifiers for said sources and a common direct current work circuit, of means for rendering the current continuous in each rectifier. 20
6. In a system of electrical distribution comprising sources of non-synchronous alternating electric currents, a plurality of rectifiers therefor, and a direct current work circuit, of means for regulating the flow of current in the several sources, said means comprising means for smoothing out the flow of current in the several rectifiers individually. 25
7. In a system of electrical distribution, the combination with supply sources having different numbers of phases, suitable rectifi- 30

fers for the several sources and a common direct current work circuit, of means for controlling said sources of supply for the said common work circuit.

8. In a system of electrical distribution, the combination with a plurality of alternating sources of different character, mercury vapor rectifiers therefor, and a common direct current circuit, of means for controlling the individual flow of current of one or more of said rectifiers. 30

Signed at New York in the county of New York and State of New York this 21st day of January A. D. 1913.
